UNITED STATES PATENT OFFICE

JAMES JUDSON PROVOST, OF YORK, PENNSYLVANIA

STEAM TURBINE

Application filed September 26, 1928. Serial No. 308,553.

The object of this invention is to provide a steam turbine power unit of increased efficiency, as compared with machines of the type or types usually employed, this unit including a rotor mounted on a main shaft journaled in a housing which is provided with an annular series of fixed blades, vanes, or buckets, said rotor including radially extending elements mounting turbine wheels cooperating in a special manner with the fixed blades in the housing, with means for driving the shaft from the turbine wheels.

A further object is to provide in a structure of this character, radial turbine-mounting elements having gear wheels fixed thereon for engagement with stationary annular racks at points diametrically opposite the points where the turbine wheels receive their impulse incident to the expansive force of the steam which is discharged against the blades, after having been admitted thru the shaft of the rotor, and thru a port extending to the outer portion of the rotor.

With the foregoing and other objects in view, the invention consists in the novel construction and arrangement of elements described, illustrated and claimed, it being understood that modifications may be made within the scope of the claims without departing from the spirit of the invention.

In the drawings forming part of this application:—

Figure 1 is a view of the unit in vertical section.

Figure 2 is a section on line 2—2 of Figure 1, and shows one of the axial elements mounting a turbine wheel for cooperation with stationary blades, and mounting a gear wheel for cooperation with a stationary annular rack.

Figure 3 is a section on line 3—3 of Figure 1, and thru that portion of the rotor in which the steam discharge port or channel is provided.

Figure 4 is a view showing one of the turbine wheels in elevation, with that portion of the engine structure having the steam discharge port therein.

Figure 5 is a view of one of the stationary blades or vanes.

The housing of the unit includes the elements 10 and 12 having flanges 13 and 14 connected by bolts 15, the elements 10 and 12 being provided with portions affording bearings at 16 and 17 for the main shaft 18. The shaft or hub portion of the rotor at the point 19 is provided with a bore 20 for admitting steam, which has been admitted to the bore thru a connection 21, where provision may be made for a flexible joint, if desired. The steam passes thence into channel, bore or opening 22 and is discharged thru port 24.

The housing has mounted therein an annular element 25 secured as shown at 26 and having fixed blades 27 mounted therein in an annular series. These blades are of the special construction illustrated in Figure 5 and include the edge portions 28 and 29 and the curved portion 30 against which the steam is discharged.

A plurality of turbine wheels 31 and 32 are mounted on radial elements 33 each having a reduced portion 34 engaged by the securing elements such as nuts 35. The blades or vanes 36 of the wheels cooperate directly with the blades 27, in the manner shown at the left of Figure 1, and the expansive force of the steam acts within the spaces formed between the elements 37 and the blades of the turbine wheels 31 and 32.

The axial elements 33, and especially the reduced end portions 34 thereof also provide axes of rotation of the gear wheels 38 and 39 formed with turbine wheels 31 and 32. The gear wheels just referred to mesh with annular racks 40 and 41, secured within the housing by means of any suitable devices as shown at 42.

The points of engagement between gear wheels 38 and 39 and the racks 40 and 41 are diametrically opposite the points where the turbine wheels receive their impulse due to the force of the steam jet, and the balance obtained and the results secured provide maximum efficiency, for a maximum drive from the turbine wheels thru their axial elements to the unitary structure carried by the main shaft 18, to be regarded as the driving shaft of the unit described. The central element 45 of the rotor is formed with an

annular groove 46 and diverging walls 47 for close cooperation with the stationary blades and enclosing the major portion of the series thereof to prevent the escape of steam except at the discharge point where it is deflected from the oppositely curved surfaces of the stationary and movable blades.

Having described the invention what is claimed is:

1. In a turbine engine, a housing, a shaft journaled therein, a rotor carried rigidly by the shaft and including radial elements, turbine wheels mounted on the radial elements, an annular series of stationary blades in the housing with which the turbine wheels cooperate, said rotor also including an annular device having a circumferential portion extending along the sides of the stationary blades, and means imparting rotary movement to the shaft from the turbine wheels and thru the radial elements of the rotor.
2. In a turbine engine, a housing, a shaft journaled therein, a rotor carried rigidly by the shaft and including radial elements, turbine wheels mounted on the radial elements, and on axes perpendicular of the shaft, an annular series of stationary blades in the housing with which the turbine wheels cooperate by movement on opposite sides thereof, said rotor including an annular device having a circumferential portion extending along the sides of the stationary blades at points remote from the impulse zone, and means imparting rotary movement to the shaft from the turbine wheels and thru the radial elements of the rotor.
3. In a turbine engine, a housing, a shaft journaled therein, a rotor carried rigidly by the shaft and including radial elements, turbine wheels mounted on the radial elements, an annular series of stationary blades in the housing with which the turbine wheels cooperate, said rotor also including an annular device having a circumferential portion extending along the sides of the stationary blades, this annular device having a bore and discharge port for ejecting steam radially into engagement with the stationary blades, and means imparting rotary movement to the shaft from the turbine wheels and thru the radial elements of the rotor.
4. In a turbine engine, a housing, a shaft journaled therein, a rotor carried rigidly by the shaft and including radial elements, turbine wheels mounted on the radial elements, an annular series of stationary blades in the housing with which the turbine wheels cooperate, said rotor also including an annular device having a circumferential portion extending along the sides of the stationary blades, and rack and gear mechanism for imparting rotary movement to the shaft from

the turbine wheels and thru the radial elements of the rotor.

5. In a turbine engine, a housing, a shaft journaled therein, a rotor carried rigidly by the shaft and including radial elements, 70 turbine wheels mounted on the radial elements, an annular series of stationary blades in the housing with which the turbine wheels cooperate, said rotor including a circumferential groove and an enlarged central portion enclosing the major portion of the blades of the annular series and cooperating therewith to prevent loss of steam, the steam being deflected laterally in opposite directions from the stationary blades on to the 80 blades of the turbine wheels.

6. In a turbine engine, a shaft journaled therein, a rotor carried rigidly by the shaft and including radial elements, turbine wheels mounted on the radial elements, an 85 annular series of stationary blades in the housing with which the turbine wheels cooperate, the stationary and moving blades being oppositely deflected, and means imparting rotary movement to the shaft from 90 the turbine wheels and thru the radial elements of the rotor.

In testimony whereof I affix my signature.

JAMES JUDSON PROVOST.
